UNITED STATES PATENT OFFICE.

ROBERT E. KEMPER, OF RENSSELAER, NEW YORK.

MEANS FOR ASSOCIATING SHEET-FEEDING MECHANISM WITH PRINTING-PRESSES.

1,357,459.

Specification of Letters Patent.

Patented Nov. 2, 1920.

Application filed January 5, 1920. Serial No. 349,448.

To all whom it may concern:

Be it known that I, ROBERT E. KEMPER, a citizen of the United States, residing at Rensselaer, in the county of Rensselaer and State of New York, have invented certain new and useful Improvements in Means for Associating Sheet-Feeding Mechanism with Printing-Presses; and I do hereby declare the following to be a full, clear, and exact 10 description of the invention, such as will enable others skilled in the art to which it appertains to make and use the same.

My invention consists in the novel features hereinafter described, reference being had to 15 the accompanying drawings which illustrate one embodiment of the same selected by me for purposes of illustration, and the said invention is fully disclosed in the following description and claims.

20 In the operation of printing presses in connection with automatic sheet feeding mechanism, the sheet feeding mechanism is usually located at the rear of the press adjacent to the feeding table and is permanently supported with respect to the press. If it becomes necessary for the operators to do any work in connection with that portion of the press adjacent to the automatic feeding mechanism, it is extremely difficult to 25 get access to the press between the rear end of the press and the feeding mechanism. In the case of printing presses in which a reciprocating bed is employed in conjunction with a press roller a great deal of work 30 must be done on the bed in connection with every job, necessitating the operator placing himself in trying positions, and working at great disadvantage through apertures in the sides of the press, or in the very small space 35 between the press and the feeding mechanism, usually from the side of the press. My invention is designed to obviate this difficulty by mounting the automatic sheet feeding mechanism upon a separate frame 40 which is movable into and out of operative relation with the press, and preferably laterally thereof, so as to give access to the entire rear portion of the press, the sheet feeding mechanism being preferably guided in its 45 movement into and out of operative position, and I further provide driving mechanism for the sheet feeding mechanism, comprising a driving member permanently located on the press, and operatively connected with some driving part thereof, and 50 a concentrically located driven member car- 55 ried by and permanently associated with the frame of the feed mechanism, said members being provided with interengaging parts for insuring their concentricity when 60 in operative relation and for connecting them for joint rotation. It is necessary obviously that the driven and driving members should also engage each other in timed relation, and as they may not be in this relation when brought together, owing to some 65 adjustments which may have taken place in either the feed mechanism or the press while they have been in separated relation, if the interengaging driving parts of the 70 said members were made rigid, they would either prevent the proper engagement of said parts, if they did not come together correctly, or said parts would be broken. I 75 therefore preferably provide means for insuring their proper interengagement in timed relation, and in the present embodiment of my invention I have provided the driving and driven members with arms, one of which carries a yielding projection, 80 spring actuated and movable in a direction parallel to the axis of rotation of said member, and the other member is provided with a hook shaped portion to engage said projection so that if the parts do not come together in proper relation, the spring actuated projection will yield, allowing the opposed arm to pass it, springing into place 85 thereafter and remaining in position to be caught by the arm on its next revolution. I 90 also provide the interengaging parts, the one with an overhanging portion, and the other with a correspondingly formed cut-away portion, so that when they are in engagement, they naturally tend to prevent the 95 separation of the parts, and therefore it is unnecessary ordinarily to provide any other locking means for holding the frame of the feed mechanism against lateral movement.

Referring to the drawings,

Figure 1 represents a portion of a printing press, and an automatic sheet feeding mechanism therefor constructed and arranged in accordance with my present invention.

Fig. 2 is a horizontal section of a portion of the printing press frame, and the frame of the sheet feeding mechanism showing the latter moved out of operative relation with the press, and the driving and driven members in separated relation.

Fig. 3 is an enlarged perspective view of

the driving and driven members showing them slightly separated.

Fig. 4 is a detail sectional view of the driving and driven members showing them in operative engagement.

Fig. 5 is a plan view of the driving and driven members showing the driving sprocket on the shaft of the driving member dispensing with reversing pinions shown in the other figures, which may be required in some cases in order to secure the correct direction of rotation of the driving and driven parts.

In the accompanying drawings, 1 represents the frame of a printing press, which in this instance is of the type in which the type bed indicated at 2, is reciprocated horizontally by rack and pinion or other suitable mechanism. As the particular details of the printing press do not concern the invention, it will not be further particularly illustrated or described, except to say that it is provided with the usual feeding table 3, and the usual feed roll 4 and feed belts or tapes 5 which receive the sheets and deliver them to the impression mechanism. 10 represents an automatic sheet feeding mechanism supported upon a suitable frame 11, which in this instance is provided with supporting wheels or rollers 12 having their axes extending longitudinally with respect to the press, so as to facilitate the movement of the frame 11 laterally with respect to the press, and a suitable guiding means is provided for guiding the feeding mechanism in this lateral movement into and out of operative relation with the press. In this instance I have shown a grooved track 13 which engages the wheels on one side of the frame 11, and I may use one or more of said tracks, as desired, but find that, owing to the weight of the frame and feed mechanism, a single track or guide is sufficient, and this is permanently secured to the floor by screws, or otherwise, in fixed relation with the press. In the present instance I have shown a sheet feeding mechanism constructed and operating exactly as illustrated and described in my former Patent #1,180,299, dated April 25, 1916. I do not, however, limit myself to the use of the present invention with any particular kind of sheet feeding mechanism, and as the sheet feeding mechanism itself has no bearing on the present invention, it is unnecessary to describe either its construction or operation except to say that sheets are delivered thereby from a pile, indicated at 14, to the feed mechanism 4—5 on the feeding table and conducted thereby, or in any other desired way to the impression devices of the press.

In order to drive the feeding mechanism from the press when in operative relation therewith, and to permit the lateral movement of the feeding mechanism, I have

shown the following instrumentalities. 15 represents the driving member which comprises a shaft mounted in a bracket 16 secured to the frame of the press, and operatively connected with a rotary part of the press, as the shaft 6 in Fig. 1. If the shaft 6 or other rotary part of the press does not rotate in the same direction as that desired for the shaft 15, I provide the shaft 15 with a pinion 17 engaging a pinion 18 on a stud 19 carrying a sprocket wheel 20 connected by chain 21 with a sprocket wheel 7 on the shaft 6 so as to secure the desired direction of rotation with the driving member. If, however, the shaft 6 turns in the same direction as that desired for the driving member, the pinions 17—18 and shaft 19 may be omitted and the sprocket and other driving wheel can be mounted directly on the shaft 15, as indicated at 20^a in Fig. 5. The shaft 15 or driving member carries in this instance an arm 22 having a hook-shaped portion 23, and the driving member is also provided with a concentric projection 24.

The frame of the sheet feeding mechanism 90 is provided with a driven member 25, which in this instance is a shaft carried in brackets extending from the frame 11 and connected by means of sprocket 26 and sprocket chain 27 with a sprocket wheel 28 on a counter shaft 29, which is in turn connected by suitable sprocket gearing including the chain 30 with the driving shaft 31 of the sheet feeding mechanism 10, or the connection between the driven shaft 25 and the sheet feeding mechanism can be made in any other preferred way. The shaft 25 is provided with a concentric recess 32 engaged by the projection 24 from the driving member when the parts are in operative relation, as shown in Figs. 4 and 5. The shaft 25 is also provided with an arm 33 carrying at its outer end a spring pressed pin or projection 34 mounted in a recess in the arm 33, and pressed outwardly by a spring 35 to its normal position, in which it is held by collar 36. The outer end of the projection 34 is preferably of larger diameter than the inner end and the hook-shaped portion 23 of the other arm 22 is cut-away adjacent to its outer face to accommodate this enlarged portion of the projection 34, as indicated at X in Figs. 4 and 5, so that the pin or projection 34 has an overhanging portion to engage a correspondingly cut-away portion of the opposed arm. When, therefore, the parts are in driving engagement, the driving pressure of the hook-shaped portion 23 of the arm 22 on the projection 34 will prevent the arms 22 and 33 from separating and hold them in operative relation so that they will not become separated by jars or accidental pressure against the feed mechanism. It will therefore be ordinarily unnecessary to provide locking means for hold-

ing the feed mechanism in operative relation with the press. I may, however, provide such locking mechanism if desired, which may rigidly connect the frame 11 and the press frame 1, or may connect the frame 11 to the flooring against lateral movement, as preferred.

It is obvious from the foregoing description that when it is desired to get access to the rear portion of the press, as for example, to do some work on the reciprocating bed, or to otherwise require the operator to have access to the rear end of the press, the automatic sheet feeding mechanism can be simply pushed laterally completely away from the rear end of the press, so as to give access thereto, without uncoupling or unfastening any parts, and the operator can perform such work as may be necessary on the press, as well as if the sheet feeding mechanism were not connected with the machine. When it is desired to use the sheet feeding mechanism, it is only necessary to move it back into its position in rear of the press so as to reengage the driving and driven members 15—22 and 25—33. It will frequently happen that owing to some movement of the press, effected by the operator, while the parts are separated, the driving and driven members will not be in position to correctly reengage. If, however, the projection 34 engages on either side of the arm 22, the arm will engage said projection at the proper point in its revolution, and the parts will proceed in timed relation. If, however, the projection or pin 34 strikes against the face of the arm 22, it will simply yield to permit the driving and driven members to come together, the concentric projection 24 entering the concentric recess 32. When power is applied to the driving member by starting the press, the arm 22 will simply slip off the end of the projection 34, which will spring into its normal position, and will be engaged by the hook-shaped portion 23, when it comes around in the next revolution, thereby taking up the operation of the driven member in proper timed relation. My invention will be found of great benefit, advantage, and convenience in the operation of presses in conjunction with automatic feeding apparatus, and will obviate the present serious difficulties which are being experienced where the feeding mechanism is permanently located with respect to the press.

What I claim and desire to secure by Letters Patent is:—

1. The combination with a printing press, of an automatic sheet feeding mechanism therefor, provided with supporting means independent of the press, said sheet feeding mechanism and its supporting means being movable bodily toward and from the press, and driving means for the sheet feeding

mechanism comprising a driving member located on and supported by the press and operatively connected with a rotary part thereof, and a separate driven member located on and supported by the sheet feeding mechanism, and maintained by the independent supporting means thereof in position to detachably engage the driving member when the sheet feeding mechanism is in operative relation with the press, whereby said members may be disengaged, and said sheet feeding mechanism may be moved bodily away from the press to afford access to the press when desired.

2. The combination with a printing press, of an automatic sheet feeding mechanism therefor, provided with supporting means independent of the press, said sheet feeding mechanism and its supporting means being movable bodily toward and from the press, and driving means for the sheet feeding mechanism comprising a driving member located on and supported by the press and operatively connected with a rotary part thereof, and a separate driven member located on and supported by the sheet feeding mechanism, and maintained by the independent supporting means thereof in position to detachably engage the driving member when the sheet feeding mechanism is in operative relation with the press, whereby said members may be disengaged, and said sheet feeding mechanism may be moved bodily away from the press to afford access to the press when desired, and guiding means for controlling the movement of said sheet feeding mechanism bodily away from and toward the press, and facilitating the reengagement of said driving and driven members, after the separation thereof.

3. The combination with a printing press, of an automatic sheet feeding mechanism therefor, provided with supporting means independent of the press, said sheet feeding mechanism and its supporting means being movable bodily toward and from the press, and driving means for the sheet feeding mechanism comprising a driving member located on and supported by the press and operatively connected with a rotary part thereof, and a separate driven member located on and supported by the sheet feeding mechanism, and maintained by the independent supporting means thereof in position to detachably engage the driving member when the sheet feeding mechanism is in operative relation with the press, whereby said members may be disengaged, and said sheet feeding mechanism may be moved bodily away from the press to afford access to the press when desired, the said driving and driven members being provided with interengaging parts, one of which is capable of yielding to facilitate the reengagement of said parts after separation.

4. The combination with a printing press, of an automatic sheet feeding mechanism therefor, provided with supporting means independent of the press, said sheet feeding mechanism and its supporting means being capable of bodily movement laterally of the press away from the same to give access to the press, and driving means for the sheet feeding mechanism comprising a driving member supported on the press and a driven member supported by the independent supporting means for the sheet feeding mechanism and operatively connected therewith, said members having their axes in alinement 10 with each other and in a line parallel to the line of bodily movement of the sheet feeding mechanism toward and from the press, said members being provided with means for detachably engaging each other when the feeding mechanism is in operative relation with the press.

5. The combination with a printing press, of an automatic sheet feeding mechanism therefor, movable bodily with respect to the press to afford access to the latter, and driving means for the sheet feeding mechanism comprising a rotary driving member located on the press and operatively connected with a rotary part thereof, a rotary driven member mounted on and operatively connected with the sheet feeding mechanism and movable with the same into and out of operative relation with the driving member, one of said members being provided with an eccentrically located projection and the other of said members being provided with an eccentrically located portion for operatively engaging said projection to transmit power from the driving to the driven member.

6. The combination with a printing press, of an automatic sheet feeding mechanism therefor, movable bodily with respect to the press to afford access to the latter, and driving means for the sheet feeding mechanism comprising a rotary driving member located on the press and operatively connected with a rotary part thereof, a rotary driven member mounted on and operatively connected with the sheet feeding mechanism and movable with the same into and out of operative relation with the driving member, one of said members being provided with an eccentrically located projection and the other of said members being provided with an eccentric part for engaging said projection, one of said interengaging parts being yieldingly supported to facilitate the interengagement of said parts when the sheet feeding mechanism is moved into operative relation with the members.

7. The combination with a printing press, of an automatic sheet feeding mechanism therefor, movable bodily with respect to the press to afford access to the latter, and driv-

ing means for the sheet feeding mechanism 65 comprising a rotary driving member located on the press and operatively connected with a rotary part thereof, a rotary driven member mounted on and operatively connected with the sheet feeding mechanism and movable with the same into and out of operative relation with the driving member, the direction of movement of the sheet feeding mechanism into and out of operative relation with the members being parallel to the axes 70 of the driving and driven members, said members being provided the one with a projection located eccentrically and capable of yielding in a direction parallel to its axis of rotation, and the other of said members 75 being provided with an eccentrically disposed portion for engaging said projection.

8. The combination with a printing press, of an automatic sheet feeding mechanism therefor, movable bodily with respect to the press to afford access to the latter, and driving means for the sheet feeding mechanism comprising a rotary driving member located on the press and operatively connected with a rotary part thereof, a rotary driven member mounted on and operatively connected with the sheet feeding mechanism and movable with the same into and out of operative relation with the driving member, the movement of said sheet feeding mechanism into 85 and out of operative relation with the press being in a direction parallel to the axes of rotation of said members, one of said members being provided with an eccentrically located projection, and the other being provided with an eccentrically located portion 90 for engaging said projection, said interengaging parts being provided with means for preventing them from separating in a direction 95 parallel to their axes of rotation, when 100 in operative engagement.

9. The combination with a printing press, of an automatic sheet feeding mechanism therefor, movable bodily with respect to the press to afford access to the latter, and driving means for the sheet feeding mechanism comprising a rotary driving member located on the press and operatively connected with a rotary part thereof, a rotary driven member mounted on and operatively connected 110 with the sheet feeding mechanism and movable with the same into and out of operative relation with the driving member, the movement of said sheet feeding mechanism into 115 and out of operative relation with the press being in a direction parallel to the axes of rotation of said members, one of said members being provided with an eccentrically located projection, and the other being provided with an eccentrically located portion 120 for engaging said projection, said projection being provided with an overhanging portion, and the contacting portion of the other mem- 125

ber being correspondingly formed to hold said members when in operative engagement against movement away from each other.

10. The combination with a printing press, 5 of an automatic sheet feeding mechanism therefor, movable laterally and bodily with respect to the press, to give access thereto, a driving member located on the press, and comprising a rotary part operatively connected with a rotary part of the press, a concentric driven member operatively connected with the sheet feeding mechanism, and carried thereby, movable with the sheet feeding mechanism into and out of operative relation with the driving member and comprising a rotary part, an arm carried by each of said rotary parts, one of said arms being provided with an eccentric projection in the path of the other arm.
- 15 11. The combination with a printing press, of an automatic sheet feeding mechanism therefor, movable laterally and bodily with respect to the press, to give access thereto, a driving member located on the press, and comprising a rotary part operatively connected with a rotary part of the press, a concentric driven member operatively connected with the sheet feeding mechanism, and carried thereby, movable with the sheet feeding mechanism into and out of operative relation with the driving member and comprising a rotary part, an arm carried by each of said rotary parts, one of said arms being provided with an eccentric projection in the path of the other arm.
- 20 12. The combination with a printing press, of an automatic sheet feeding mechanism therefor, movable laterally and bodily with respect to the press, to give access thereto, a driving member located on the press, and comprising a rotary part operatively connected with a rotary part of the press, a concentric driven member operatively connected with the sheet feeding mechanism, and carried thereby, movable with the sheet feeding mechanism into and out of operative relation with the driving member and comprising a rotary part, an arm carried by each of said rotary parts, one of said arms being provided with an eccentric projection in the path of the other arm, said projection being movable in a direction parallel to the axis of rotation of said rotary arms, and a spring for holding said projection in operative position with respect to the other arm.
- 25 13. The combination with a printing press, of an automatic sheet feeding mechanism therefor, mounted on a separate frame movable bodily laterally with respect to the press, guiding means for guiding the sheet feeding mechanism in its lateral movement, 70 driving means for the sheet feeding mechanism comprising a rotary driving member located on the press and operatively connected with the rotary part thereof, a driven member carried by the frame of the sheet feeding mechanism and movable with the same into and out of operative relation with the driving member and operatively connected with the sheet feeding mechanism, said members being each provided with an 75 arm, and one of said members being provided with a concentric projection, and the other with a concentric recess for engaging the same, one of said arms being provided with an eccentric driving projection 80 provided with an overhanging portion, and movable in a direction parallel with the axis of rotation of said member, and a spring 85 engaging said projection and holding it in operative position, the other arm being provided with a hook-shaped portion for engaging said projection, said hook-shaped portion being cut away adjacent to the outer side to engage the overhanging portion of said projection and hold said arms against 90 movement away from each other when said members are in driving relation.
- 30 14. The combination with a printing press, of an automatic sheet feeding mechanism therefor, movable laterally and bodily with respect to the press, to give access thereto, a driving member located on the press, and comprising a rotary part operatively connected with a rotary part of the press, a concentric driven member operatively connected with the sheet feeding mechanism, and carried thereby, movable with the sheet
- 35 15. The combination with a printing press, of an automatic sheet feeding mechanism therefor, mounted on a separate frame movable bodily laterally with respect to the press, guiding means for guiding the sheet feeding mechanism in its lateral movement, 70 driving means for the sheet feeding mechanism comprising a rotary driving member located on the press and operatively connected with the rotary part thereof, a driven member carried by the frame of the sheet feeding mechanism and movable with the same into and out of operative relation with the driving member and operatively connected with the sheet feeding mechanism, said members being each provided with an 75 arm, and one of said members being provided with a concentric projection, and the other with a concentric recess for engaging the same, one of said arms being provided with an eccentric driving projection 80 provided with an overhanging portion, and movable in a direction parallel with the axis of rotation of said member, and a spring 85 engaging said projection and holding it in operative position, the other arm being provided with a hook-shaped portion for engaging said projection, said hook-shaped portion being cut away adjacent to the outer side to engage the overhanging portion of said projection and hold said arms against 90 movement away from each other when said members are in driving relation.
- 40 16. The combination with a printing press, of an automatic sheet feeding mechanism therefor, movable laterally and bodily with respect to the press, to give access thereto, a driving member located on the press, and comprising a rotary part operatively connected with a rotary part of the press, a concentric driven member operatively connected with the sheet feeding mechanism, and carried thereby, movable with the sheet
- 45 17. The combination with a printing press, of an automatic sheet feeding mechanism therefor, mounted on a separate frame movable bodily laterally with respect to the press, guiding means for guiding the sheet feeding mechanism in its lateral movement, 70 driving means for the sheet feeding mechanism comprising a rotary driving member located on the press and operatively connected with the rotary part thereof, a driven member carried by the frame of the sheet feeding mechanism and movable with the same into and out of operative relation with the driving member and operatively connected with the sheet feeding mechanism, said members being each provided with an 75 arm, and one of said members being provided with a concentric projection, and the other with a concentric recess for engaging the same, one of said arms being provided with an eccentric driving projection 80 provided with an overhanging portion, and movable in a direction parallel with the axis of rotation of said member, and a spring 85 engaging said projection and holding it in operative position, the other arm being provided with a hook-shaped portion for engaging said projection, said hook-shaped portion being cut away adjacent to the outer side to engage the overhanging portion of said projection and hold said arms against 90 movement away from each other when said members are in driving relation.
- 50 18. The combination with a printing press, of an automatic sheet feeding mechanism therefor, mounted on a separate frame movable bodily laterally with respect to the press, guiding means for guiding the sheet feeding mechanism in its lateral movement, 70 driving means for the sheet feeding mechanism comprising a rotary driving member located on the press and operatively connected with the rotary part thereof, a driven member carried by the frame of the sheet feeding mechanism and movable with the same into and out of operative relation with the driving member and operatively connected with the sheet feeding mechanism, said members being each provided with an 75 arm, and one of said members being provided with a concentric projection, and the other with a concentric recess for engaging the same, one of said arms being provided with an eccentric driving projection 80 provided with an overhanging portion, and movable in a direction parallel with the axis of rotation of said member, and a spring 85 engaging said projection and holding it in operative position, the other arm being provided with a hook-shaped portion for engaging said projection, said hook-shaped portion being cut away adjacent to the outer side to engage the overhanging portion of said projection and hold said arms against 90 movement away from each other when said members are in driving relation.

In testimony whereof I affix my signature.

ROBERT E. KEMPER.
